JAMES C. MOOREHEAD AND WILLIAM W. ELLIOTT, OF NEW MADRID,
MISSOURI.

Letters Patent No. 77,075, dated April 21, 1868.

IMPROVEMENT IN FEATHER-RENOVATOR.

The Schedule referred to in these Letters Patent and making part of the same.

TO ALL WHOM IT MAY CONCERN:

Be it known that we, JAMES C. MOOREHEAD and WILLIAM W. ELLIOTT, of the city and county of New Madrid, and State of Missouri, have invented a new and improved Feather-Renovator; and we do hereby declare that the following is a full, clear, and exact description of the construction and operation of the same, reference being had to the annexed drawings, making a part of this specification, in which—

Figure 1 is an end view, a portion of the wall having been broken away.

Figure 2 is an axial section of the cylinder.

Figure 3 is a cross-section of the same.

Figure 4 is a cross-section of the steam-boiler.

In this invention two boilers are employed, one containing pure water, and the other containing certain chemicals in solution. The steam from these boilers is carried in separate pipes to the cylinder, where the jets are united and discharged among the feathers. The latter are beaten and shaken, while under the action of the steam, until thoroughly cleansed.

In the drawings, A represents a sheet-iron stove, about eighteen inches in width, twenty-one in height, and twenty-four in length, and provided with two transverse rods, *a a*, seven inches from the top, to support the steam-boiler, B.

The latter is about seventeen inches in diameter and twenty-four in height, and is divided into two parts, *b* and *b'*, by a transverse partition, four and a half inches from its upper end. Several flues, C C, pass through the part *b*, being open at both ends, and allowing the smoke, heat, &c., to pass from the fire in the stove to the chamber *b'*, and thence to the open air, through the smoke-flue E.

D is a cylindrical tin boiler, about eight inches in diameter and nine in height, which sits in the top of the boiler B, as seen in fig. 1, receiving heat from the hot air, &c., passing through the chamber *b'*. The lower boiler is for the purpose of generating steam from pure water, and the upper one is for the purpose of generating steam from a solution of chemicals. Both boilers are provided with feed-pipes, *ff'*, and with steam-pipes, G G', through which the steam from each is carried to the feathers.

I is a horizontal cylinder, about eight feet long and twenty-eight inches in diameter, its periphery being composed of staves or slats of wood, *i i*, slightly separated, so that the dirt and steam can pass out between them. The cylinder is hung upon a tubular revolving axle or shaft, J, with which both steam-pipes connect, as shown at *g*. Two or more bent pipes, K K', extend from near one end of the shaft, within the cylinder, out towards the perimeter of the latter, then back to the opposite end of the cylinder to which they are attached, as shown at *k k*. Each of these pipes is perforated along its outer side, as seen at *m m*, and is provided with a series of slide-valves, *o o*, connected by a rod, *n*, the end of which passes through one end of the cylinder, and forms a handle by which the valves can be adjusted, so as to admit any required amount of steam to the feathers. The ends of these pipes are closed, but are provided with stop-cocks, *r r*, to permit the condensed steam to escape.

The method of operating this machine is as follows: We fill the steam-boiler B with the proper quantity of water, then place in the chemical-boiler D two gallons of pure water, one-fourth ounce chloride of lime, one-fourth ounce nitrate of potassa, one-fourth ounce cream of tartar, the latter having been dissolved in one pint of warm water. We bring the liquids in both vessels to a boil, and commingle their steam in the shaft J, as above described, the valves *o o* being closed. We then empty the feathers into the cylinder, by means of a door, P, in the perimeter of the latter, set the cylinder in motion, and open the valves *o o*, letting on the steam, which moistens the feathers while the cylinder revolves. When they have been subjected to this action twenty-five minutes, we close the valves *o o*, and keep the cylinder in motion about half an hour, which thoroughly dries the feathers, when they are removed from the cylinder, and are found to be thoroughly cleansed and renovated.

Having thus described our invention, what we claim as new, and desire to secure by Letters Patent, is—

1. In a machine for renovating feathers, we claim the combination of the water-boiler B with the chemical-boiler D and the pipes G G', for the purpose of generating, conveying, and uniting the two kinds of steam, preparatory to subjecting the feathers to their joint action.
2. The cylinder I, when constructed of slats *i i i*, slightly separated, in the manner and for the purpose set forth.
3. The combination, within a revolving cylinder, of the tubular shaft J with the pipes K K', the latter being provided with valves *o o o*, substantially as and for the purpose set forth.
4. The combination of the boilers D D, pipes G G', cylinder I, shaft J, pipes K K', valves *o o o*, and stop-cocks *r r*, substantially as and for the purpose set forth.
5. We claim the method of purifying and renovating feathers, substantially as herein described.

The above specification of our invention signed by us, this 22d day of February, 1868.

JAMES C. MOOREHEAD,
WILLIAM W. ELLIOTT.
